Primary Examiner — Ricky Pham(74) *Attorney, Agent, or Firm* — Heslin Rotherberg Farley & Mesiti P.C.(57) **CLAIM**

The ornamental design for a chair, as shown and described.

DESCRIPTION

FIG. 1 is a perspective view of the chair of the present invention;

FIG. 2 is a front elevation view thereof;

FIG. 3 is a right side elevation view thereof, the left side elevation view being a mirror image thereof;

FIG. 4 is a rear elevation view thereof;

FIG. 5 is a top plan view thereof; and,

FIG. 6 is a bottom plan view thereof.

The broken lines in the figures are for illustrative purposes only and form no part of the claimed invention.
